UNITED STATES PATENT OFFICE.

CARLEY G. WELD, OF NORTH CHATHAM, MASSACHUSETTS.

PUMP.

1,163,724.

Specification of Letters Patent. Patented Dec. 14, 1915.

Application filed February 28, 1910. Serial No. 546,358.

To all whom it may concern:

Be it known that I, CARLEY G. WELD, a citizen of the United States, residing at North Chatham, in the county of Barnstable and State of Massachusetts, have invented new and useful Improvements in Pumps, of which the following is a specification.

This invention relates to improvements in pumps of that class which are used in combination with a suitable engine having one or more cylinders, one of which is in communication with the pump cylinder and by reason of such communication the pump piston is reciprocated by the alternate increase and diminution of pressure within the engine cylinder with which the pump cylinder communicates.

The pump which forms the subject matter of my invention is particularly intended and adapted for inflating tires of motor vehicles in which case the pump cylinder is connected to one of the cylinders of the engine of the vehicle whether said engine be of the steam type or the internal combustion type.

The object of my invention is to provide a pump of the class described which shall be simple in construction and quiet in operation, and the object is further to provide a pump so constructed that only pure air shall be pumped into the tires.

The invention consists in the novel features of construction and in the combination and arrangement of parts set forth in the following specification and particularly pointed out in the claims.

Referring to the drawing: Figure 1 is an elevation of a pump embodying my invention, the same being shown connected to an internal combustion engine. Fig. 2 is an enlarged detail sectional view of the pump taken on line 2—2 of Fig. 1.

In the illustration, a cylinder-casing 5, is shown, in which the body 6, is mounted to reciprocate free from restraint. The cylinder-casing is shown of two diameters. One portion 7, is of a larger diameter than is the other portion 8, thus forming two cylinders or chambers as it were, within the casing, the casing being open from end to end. In the present illustration, the two portions of the cylinder-casing are made separable one from the other and are connected by means of a screw-threaded joint. The cylinder or chamber 7, will be open to some expansive force subject to variations which will pro-

duce the reciprocation of the body 6. The body 6 is shown made up of a pair of pistons 9 and 10, connected by means of a bar or rod 11. The piston 9 is provided with suitable piston-rings 12, and the piston 10 is provided with a suitable cup-leather 13. In practice the cylinder or chamber 7 will be the expansion chamber or operating element of the pump, and the cylinder or chamber 8 will be the compression or operated chamber. The cup-leather will be located in such position that in the forward or compression movement, backflow of fluid will be prevented, but upon the return or idle movement of the piston, air may pass into the cylinder 8, past the cup-leather 13, from the openings 14, which communicate with the outside air.

The outer end of the chamber or cylinder 8 is provided with an outlet 15, communicating with a connection 16. A back-pressure-valve 17, held on its seat by a spring 18, will be provided for the outlet 15. A suitable screw-cap 19, will hold the spring 80 and valve in place.

In practice the pump may be secured to one of the cylinders 21, of an internal combustion engine 22, by means of a screw-threaded connection 23, which has an internal-bore 20, in connection with the end of the cylinder or chamber 7.

When it is desired to use the pump in connection with an internal combustion engine, a spark-plug will be taken from one of the cylinders and the connection 23 inserted in the place from which the spark-plug was removed. Upon each compression stroke of this cylinder, there will be an expansion of fluid in the chamber 7, behind the piston 9, which will drive this forward and cause the piston 10 to compress the air before it and drive this through the outlet 15, and past the valve 17. Upon the reverse movement of the piston in the engine cylinder to which the pump is connected, the piston 9 will be drawn down by means of the compression of fluid thus created, and will draw with it the piston 10, which, as before stated, upon its idle movement will permit air to pass from the openings 14 to the compression side of it.

It is to be observed that the cylinder as a whole is open from end to end; that the chamber 8 opens into the chamber 7, and that the member 6 is free to reciprocate within the cylinder-casing without any restraint whatsoever. It will also be observed that

the member 6 is guided by means of packings of the respective pistons only. In order to prevent the pistons from striking the ends of their respective cylinders or chambers and thus causing an injurious and unpleasant hammering, means are provided for reducing the area of the inlet passage 20 and the outlet passage 15, when the piston has nearly completed its stroke toward either 10 of these passages. The piston 9 is provided with a projection 24, located in position to enter the passage 20, upon the down-stroke of the piston 9. A small amount of clearance is provided between the projection 24 15 and the passage 20, so that as the piston is drawn down and the projection 24 enters the passage 20, the outflow of the fluid between the piston and the cylinder-head will be restricted and a small amount of the fluid 20 made captive so that a cushioning effect will be provided and the piston will be stopped without shock or jar. The piston 10 carries a projection 25, located in position to enter the outlet-passage 15 at about 25 the completion of the forward or working stroke of the piston 10. Suitable clearances will be provided between the projection 25 and the outlet 15, so that the fluid under compression at about the completion of the 30 compression stroke will be retarded in its outward movement and a cushion provided between the piston 10 and the cylinder-head. There will be sufficient clearance between the projection 24 and the inlet-passage 20 to 35 permit the incoming fluid upon the working stroke to pass into the cylinder and engage the entire working area of the piston 9.

Although but one form of this invention is illustrated and particularly described, yet 40 it will be apparent that changes in construction may be made without departing from the spirit of the invention.

Having thus described my invention, I 45 claim and desire to secure by Letters Patent: 1. A pump adapted to be connected to one cylinder of a multiple cylinder internal combustion engine, comprising a casing open from end to end and having an inlet and an

outlet and embodying an expansion chamber and a compression chamber of lesser 50 diameter than said expansion chamber, said expansion chamber being provided with an inlet port located in the wall thereof, a member mounted within said casing to reciprocate free from restraint therein and 55 comprising a piston located in each of said chambers and means carried by each piston and adapted to coöperate with said inlet and said outlet respectively to retard the movement of said member in a plurality of 60 predetermined directions, said pump being functioned by the compression stroke of the piston within said engine cylinder, whereby the fluid passes from said expansion chamber past the piston in said compression 65 chamber, the fluid being compressed in said compression chamber and discharged through said outlet.

2. A pump adapted to be connected to one cylinder of a multiple cylinder internal 70 combustion engine comprising a casing embodying two portions normally connected for disassemblage one from the other, one of said portions providing an expansion chamber and the other of said portions 75 forming a compression chamber of lesser diameter than said expansion chamber, said casing being open from end to end and a member mounted within said casing to reciprocate free from restraint therein and 80 comprising a piston located in each of said chambers, the piston in said compression chamber having a cup washer mounted thereon, said pump being functioned by the operation of the piston within said engine 85 cylinder whereby the fluid flows from said expansion chamber past said compression piston into said compression chamber.

In testimony whereof I have hereunto set my hand in presence of two subscribing 90 witnesses.

CARLEY G. WELD.
